US0D1075529S

(12) **United States Design Patent** (10) **Patent No.:** **US D1,075,529 S**
(45) **Date of Patent:** **** May 20, 2025**

(54) **WIRELESS BARBECUE PROBE**

(71) Applicants: **SHENZHEN CHENGXINGTAI ELECTRICAL HEATING APPLIANCE CO., LTD**, Shenzhen (CN); **Shenzhen ElinkThings Co., Ltd**, Shenzhen (CN)

(72) Inventors: **Cheng Wang**, Shenzhen (CN); **Zhen Li**, Shenzhen (CN)

(73) Assignees: **SHENZHEN CHENGXINGTAI ELECTRICAL HEATING APPLIANCE CO., LTD**, Shenzhen (CN); **Shenzhen ElinkThings Co., Ltd**, Shenzhen (CN)

(**) Term: **15 Years**

(21) Appl. No.: **29/911,156**

(22) Filed: **Aug. 30, 2023**

(51) LOC (15) Cl. **10-04**

(52) U.S. Cl.

USPC **D10/57**
